Primary Examiner — Mark A Goodwin(74) *Attorney, Agent, or Firm* — Merchant & Gould P.C.(57) **CLAIM**

The ornamental design for a boom hose apparatus, as shown and described.

DESCRIPTION

FIG. 1 is a side view of a boom hose apparatus for a vehicle showing our new design;

FIG. 2 is a front, top, left side perspective view thereof;

FIG. 3 is a front, top, right side perspective view thereof;

FIG. 4 is a front, bottom, right side perspective view thereof;

FIG. 5 is a left side view thereof;

FIG. 6 is a right side view thereof;

FIG. 7 is a front view thereof;

FIG. 8 is a rear view thereof;

FIG. 9 is a top view thereof; and,

FIG. 10 is a bottom view thereof.

The broken line showing of a vehicle in FIG. 1 is included for the purpose of illustrating environmental structure only and forms no part of the claimed design. The dot-dash wavy broken lines are break lines that represent an indeterminate length. The curly brackets also represent an indeterminate length and form no part of the claimed design.
